UNITED STATES PATENT OFFICE

EDWARD L. COMBS, OF PHILADELPHIA, PENNSYLVANIA, ASSIGNOR TO PHILADELPHIA
STORAGE BATTERY COMPANY, OF PHILADELPHIA, PENNSYLVANIA, A CORPORATION
OF PENNSYLVANIA

DESIGN FOR A RADIOCABINET

Application filed January 15, 1932. Serial No. 42,487. Term of patent 14 years.

To all whom it may concern:

Be it known that I, EDWARD L. COMBS, a citizen of the United States, residing in Philadelphia, Pennsylvania, have invented a new, original, and ornamental Design for a Radio-cabinet, of which the following is a specification, reference being had to the accompanying drawing, forming part thereof, in which

the figure is a perspective view of a radio-cabinet made in accordance with my invention.

I claim:

The ornamental design for a radio cabinet, as shown.

EDWARD L. COMBS.
